UNITED STATES PATENT OFFICE

ARTHUR W. ZERBY, OF READING, PENNSYLVANIA

HOSIERY BOX

Application filed June 6, 1928. Serial No. 283,322.

- This invention relates to improvements in boxes and it pertains more particularly to boxes intended to receive and display women's hosiery.
- 5 The invention consists of a plurality of so-called "frogs" located inside the lower portion of a hosiery box, and so arranged that when the stocking is folded, the toe and heel portions will be received in and held in the spaces ordinarily intended for them, while the leg portion, when properly folded will lie in the box and abut against the squared ends of a pair of oppositely disposed frog members, to effectually prevent 15 sliding or rolling.
- The invention is more fully described in the following specification and clearly illustrated in the accompanying drawing, in which:—
- 20 Figure 1 is a plan view of the lower box member, showing the location therein of the frogs.
- Figure 2 is a like view, with one or more stockings in position therein.
- 25 Figure 3 is a longitudinal, central sectional view of the box.
- The numeral 1 designates the lower portion of the box, into which the stockings are to be placed.
- 30 2 designates the end frog, of substantially triangular form, to provide two tapered walls 3.
- 4 designates a pair of oppositely disposed frog members, located at the same end of the box as is the aforementioned triangular member, and in close proximity thereto. These members 4 are each formed with a tapered end 6, at that end which approaches the triangular member, but sufficiently spaced 35 therefrom to provide a pair of heel and toe receptacles 7 for the folded stockings. The rear ends of the members 4 are cut off at right angles to the body, forming a pair of abutments 8, against which the folded leg portions of the stockings will bear when the stockings are properly folded and inserted in the box.
- The stockings are folded and laid in the box with the toe and heel portions alternately arranged, as indicated in Figure 2
- of the drawing, and the leg portions, being considerably wider, will extend the full width of the box, at the rear of the abutments of the members 4 and this structure will prevent the sliding or slipping of the 55 folded stockings.
- The frog members may be made integral with the box, or they may be made of separate pieces of material and inserted therein, the essential feature being to so locate them at one end of the box, that the toe and heel portions will be properly housed while the leg portions will be prevented from rolling or piling up upon 65 themselves.
- Having thus fully described my invention, what I claim and desire to secure by Letters Patent is:—
1. In a hosiery box for women's stockings, a body portion, and a plurality of frog members located inside thereof, at one end, said frog members having tapered walls to form receiving spaces for the toe and heel portions of the folded stockings, and two of said frog members having right 75 angled abutments to engage and prevent movement of the folded leg portions of the stockings.
2. In a hosiery box, the combination of a body portion, a triangular frog located at 80 one end thereof and a pair of oppositely disposed side frogs at the same end of the body and in close proximity to the triangular frog, said frogs having tapered faces to form receiving spaces for the heel and toe 85 portions of the stockings, and the side frogs having squared rear ends to form abutments for the leg portions of the folded stockings.
- In testimony whereof I affix my signature.
- ARTHUR W. ZERBY. 90
